FLEXIBLE BUCKET TOOTH CONNECTION

Charles F. Swigert, Jr., Portland, Oreg., assignor
to Electric Steel Foundry Company, Portland,
Oreg.

Application October 28, 1935, Serial No. 47,051

3 Claims. (Cl. 37—142)

This invention relates generally to excavating machinery and particularly to a flexible bucket tooth connection.

The main object of this invention is the reduction in the amount of breakage which ordinarily occurs when a solid shank is employed.

The second object is to reduce the cost of replacing a casting in case the tooth point should become broken or worn away.

10 The third object is the construction of a tooth connection in which the shank and tooth are separate pieces and the part which requires replacement, namely, the point, is relatively small; thereby securing a considerable saving in transportation.

15 The fourth object is to eliminate the tendency for the securing wedge to loosen under digging strains which, if transmitted through a solid shank, exert a continual vertical pressure against the side of the wedge. With a flexible shank these strains are absorbed at the flexible connection and no vertical pressure is applied to the wedge.

20 The fifth object is the construction of a tooth point in which the shape is such as to insure a more uniform and dense structure in the casting than is possible with the old style of heavy solid shank.

25 The sixth object is to improve the point itself by eliminating a heavy portion of the metal and making it possible to keep the metal section quite uniform. When the metal section is not uniform, some of the parts retain their heat and plastic condition long after thinner parts have become solidified, causing cracks and soft spots to occur.

30 The seventh object is to so construct the tooth that absolute precision is not necessary between the cored recess and the inserted parts in order to secure a proper assembly of the parts.

35 The eighth object is to so construct the tooth that the stress on the support for the tooth point is entirely in tension without any bending, thereby making it possible to make a lighter metal section than would be necessary where bending stress must be provided for.

40 These, and other objects, will become more apparent from the specification following as illustrated in the accompanying drawings, in which:

45 Fig. 1 is a longitudinal section through a tooth and support taken along the line 1—1 in Fig. 2.

50 Fig. 2 is a section taken along the line 2—2 in Fig. 1.

55 Fig. 3 is a fragmentary perspective view of a point holder.

Fig. 4 is a perspective view of the flexible tooth point shank.

Fig. 5 is a perspective view showing a tooth point shank placed in position for insertion into the tooth point which is shown in cross section.

Fig. 6 is a view similar to Fig. 5 but showing the tooth point shank partly inserted into the tooth point.

Fig. 7 is a view similar to Fig. 6 but showing the tooth point shank fully inserted into the tooth point.

Fig. 8 is a section showing the tooth point shank being inserted into the point holder.

Fig. 9 is a section taken along the line 9—9 in Fig. 1.

15 Similar numbers of reference refer to similar parts throughout the several views.

Referring in detail to the drawings, there is shown a point holder 10 which is formed on the bucket lip 11 and has projecting from the holder 10 the spaced parallel arms 12 which terminate in the rounded arms 13. The edges 14 of the arms 12 are somewhat narrower than the thickness of the arms 12 and are provided with the shoulders 15. Extending through the point holder 10 is an opening 16 which intersects the cored recess 17 which forms a continuation of the space between the arms 12.

20 It is desirable to taper the opening 16 to receive the wedge 18 whose point 19 is slit to permit the spreading thereof for retaining purposes. It is also desirable to flare the end 20 of the opening 16, within which flared portion 20 the parts of the point 19 can be spread.

25 Referring particularly to the point 21 itself, this may assume any external shape, but in the form illustrated the face 22 is in parallelism with the face 23 of the holder 10 and the face 24 is tangent to the curved side 25 of the holder 10. The point 21 is provided with a central recess 26 and the end walls 27 thereof are provided with the cut out portions 28, which receive the outer portions 29 of the arms 12. Within the recess 26 is disposed a web 30 whose outer end 31 is rounded. The web 30 is provided with an opening 32 near the end 33 of the recess 26.

30 Referring particularly to the tooth point shank 34, same will be seen to consist of an elongated forked bar whose ends 35 have inturned lugs 36 formed thereon, which lugs 36 are inclined on the outer sides 37 to facilitate their reception of the web 30 when the parts are brought together.

35 The operation of the device is as follows:

40 In assembling the tooth point shank 34 upon the point 21 the parts are brought into the rela-

tion shown in Fig. 5 and the shank 34 is forced toward the recess 38, causing the ends 36 to separate and finally to latch into the opening 32 as shown in Fig. 7. There is a sufficient spring in 5 the shank 34 to permit this action.

When assembling the tooth point 21 with its attached shank 34 upon the tooth holder 10, it is only necessary to insert the shank 34 into the recess 17 and then drive the wedge 18 into place 10 and spread the points 16 as shown in Fig. 1.

It will be understood that the shank 34 is very loose within the recess 17 and that when the wedge 18 is in place the shank 34 is only in tension and that the interior walls 33 of the point 21 15 bear securely against the edges 14 of the arms 12 of the holder 10.

The flexible connection between the point 19 and the shank 34 permits this bearing to be taken up evenly on the bearing surfaces of both of the 20 arms 12, even though these arms are not in exact relationship with the recess 17. When a solid shank is used the point 19 can be drawn up on the holder 10 in an axial line only, and if one arm 12 is slightly forward of the other, contact will be 25 taken by this arm only, thus subjecting the arm to excessive stresses and the shank to a severe bending.

While I have shown the wedge 18 as being driven in from the top, it is obvious that it could be 30 driven in from the side without departing from the spirit of this invention. It is also obvious that this improved point could be used in connection with adaptors such as are now on the market.

35 While this point and its fastening have been referred to as a bucket tooth connection, it must be understood that it is equally adaptable to all sorts of excavating, road servicing, and agricultural machines, such as subsoilers, ploughs, scari- 40 fiers, dipper type of buckets, drag line buckets, scrapers, etc.

It will be noted that when the tooth point shank 34 is forced into position within the point 21, it takes a permanent set in a slightly spread position although it does have sufficient spring to latch the inturned lugs 36 into the opening 32. However, when the tooth point shank 34 is inserted into the recess 17, the ends 36 engage the sides 33 of the recess 17 and the lugs 36 are forced together thereby, positively insuring against any unlatching between the tooth point shank 34 and the point 21.

I claim:

1. A bucket tooth point having a recess in one end thereof and having a perforated web within said recess and a forked shank for said point having inturned ends adapted to latch in the perforations of said web for the purpose of forming a loose connection between said point and shank.

2. A bucket tooth point having a recess formed at one end thereof, two sides of which converge and having a web formed between said converging sides, said web having an opening through the inner end thereof, a forked shank for said tooth having the open ends thereof inturned, said forked shank being capable of opening sufficiently to permit said web to pass between said inturned ends and to latch within the opening formed within said web.

3. In a bucket tooth of the class described a point having a tapering recess and having a web between the tapering sides of said recess provided with an opening through the inner end of the web and an elongated forked shank having inturned latching ends at the open end thereof adapted to receive said web between same when said shank is forced into said point and to latch said inturned ends into said web opening for the purpose of forming a hinged joint between said shank and joint.

CHARLES F. SWIGERT, JR.
